UNITED STATES PATENT OFFICE.

ARTHUR MIDDLETON ROSE, OF YONKERS, NEW YORK, ASSIGNOR TO McCALLUM & McCALLUM, OF PHILADELPHIA, PENNSYLVANIA.

DESIGN FOR CARPET.

SPECIFICATION forming part of Design No. 24,416, dated June 18, 1895.

Application filed March 4, 1895. Serial No. 540,530. Term of patent 3½ years.

To all whom it may concern:

Be it known that I, ARTHUR MIDDLETON ROSE, a citizen of the United States, residing at the city of Yonkers, in the county of West-
5 chester and State of New York, have invented and produced a new and original Design for a Carpet or other Fabric, of which the following, taken in connection with the accompanying drawing, is a specification.

10 The design of my invention can be fully represented by illustration. Accordingly for a description of it I refer to the accompanying drawing, in which—a is the body, b the border, and a and b the 15 complete carpet.

My design may be expressed in various colors or combinations of colors and applied to the surface of Wilton, Brussels, velvet or other carpets.

20 The leading or characteristic feature of my design may be said to be the flowers c—d, displayed upon a background e, and in the drawing associated with bands f and g.

What I claim as new, and desire to secure by Letters Patent, is—

1. In the design for a carpet the body a, substantially as shown.
2. In a design for a carpet the border b, substantially as shown.
3. The design for a carpet consisting of the 30 body a, and the border b, substantially as shown.

In testimony whereof I have hereunto signed my name in the presence of two witnesses.

ARTHUR MIDDLETON ROSE.
